DESIGN FOR A BROOCH PIN OR SIMILAR ARTICLE

Ray K. de Caracena, Bronx, N. Y.

Application March 15, 1939, Serial No. 83,581

Term of patent 7 years

To all whom it may concern:

Be it known that I, Ray K. de Caracena, a citizen of the United States, residing in the Bronx, county of Bronx and State of New York, have invented a new, original, and ornamental Design for a Brooch Pin, or Similar Article, of which the following is a specification, reference being had to the accompanying drawing, forming part thereof.

Figure 1 is a plan view of a brooch pin or similar article, showing my new design, and

The dominant features of the design reside in the portions shown in solid lines.

I claim:

The ornamental design for a brooch pin or similar article, substantially as shown and described.

RAY K. DE CARACENA.
